UNITED STATES PATENT OFFICE.

HARRY C. GAMMETER, OF CLEVELAND HEIGHTS, OHIO, ASSIGNOR TO THE AMERICAN MULTIGRAPH COMPANY, OF CLEVELAND, OHIO, A CORPORATION OF OHIO.

METHOD OF AND APPARATUS FOR CASTING STEREOTYPE PLATES.

Application filed August 21, 1922. Serial No. 583,158.

To all whom it may concern:

Be it known that I, HARRY C. GAMMETER, a citizen of the United States, residing at Cleveland Heights, in the county of Cuyahoga and State of Ohio, have invented a certain new and useful Improvement in Methods of and Apparatus for Casting Stereotype Plates, of which the following is a full, clear, and exact description, reference 10 being had to the accompanying drawings.

This invention is concerned with the art of forming stereotypes and is directed to improvements in the apparatus of casting stereotype plates.

15 The general object of the present invention is the provision of a novel apparatus for casting thin stereotype plates of such unusual thinness that it has been considered heretofore impossible to obtain.

20 A more specific object is to accomplish the casting of these stereotype plates rapidly and accurately upon a matrix by simple, efficient and easily used means.

Another object of the present invention 25 is the provision of an apparatus for carrying out my improved method of molding stereotypes which are particularly adaptable for use on multigraph machines, the thickness of the plate from the back surface thereof 30 to the type face corresponding to the height of the usual multigraph type which is approximately $\frac{1}{16}$ of an inch.

Other objects will become apparent from the following description, in connection with 35 the accompanying drawings, which illustrate a preferred means for carrying out the steps in my method of forming stereotype plates.

It has been considered necessary, heretofore, in casting stereotype to provide a plate body or wall from $\frac{3}{8}$ to $\frac{1}{2}$ of an inch in thickness to obtain a uniform flow of cast metal from the pouring gate of the mold to the more remote surfaces of the matrix. By 40 the use of my improved method, I am able to cast stereotype plates having corresponding printing surfaces, and, in addition thereto, obtain an unusually thin body. This is effected by controlling the heat conduction 45 from the molten metal to the mold members in such a manner that a uniform cross section is obtained between the type face and the back face in all sections of the plate with an entire absence of flaws or cavities in the 50 type faces or figures.

In carrying out the steps in my process, I support a matrix, which is formed in the usual manner, upon a mold member in juxtaposition and parallel to a second mold member which defines the back surface of 60 the plate, the second member having a replaceable molding or lining surface comprising heat insulating material, such as sheet fibre, asbestos or ordinary news print paper. 65

I find, for instance, that in casting a stereotype plate having a body thickness of $\frac{1}{16}$ of an inch, that ordinarily news print paper, about three thousands of an inch in thickness, may be used to line the back 70 molding surface of the mold.

I will describe my method of forming stereotypes as applied to the casting of semi-circular stereotype plates, such as may be conveniently and economically used in 75 connection with a multigraph machine; the stereotype plates being adaptable for use in place of the usual printing form made up by assembling individual type.

A thin stereotype plate, such as I have referred to, may be conveniently and successfully cast by my method in a molding apparatus, such as is illustrated in the drawings wherein Fig. 1 is a plan view of the molding apparatus with the mold members positioned for the casting of an arcuately formed stereotype plate; Fig. 2 is a cross sectional elevation taken substantially along the line 2—2 of Fig. 1; Fig. 3 is an enlarged cross sectional view taken transversely of the mold members; Figs. 4 and 5 are fragmentary cross sectional views illustrating a convenient means for clamping or securing the matrix and non-conductive mold lining to the respective mold members; Fig. 6 is an enlarged fragmentary cross sectional view taken through the gate of the molding apparatus; Fig. 7 is a fragmentary view of a corner portion of the stereotype. 85 90 95

The molding apparatus may comprise a 100 base or supporting member 10 having one end 11 thereof formed in the manner of a pedestal which supports a drag or concave matrix supporting member 12 and a cope or convex back forming mold member 13 the 105 curved surfaces of both members being parallel when the mold is assembled. The cope and drag members are of sufficient height to provide a gate or pouring space, the cope member having an upper coniform sur- 110

face 8 extending away from the inner surface of the drag member.

The drag member is provided with matrix clamping means at each side thereof which 5 may also comprise part of the mold in forming the side margins or edges of the stereotype plate in a manner which will be presently described. The cope member is likewise provided with clamping means for 10 gaging and securing the non-conductive lining to the inner molding surface thereof. The top edge of the cast plate is defined by the level to which the molten metal is poured, there being no mechanical means shown for 15 defining this edge, a margin or trimming line, however, may be formed by the matrix.

I prefer to provide clamping means securing the matrix to the drag member which may also comprise means for defining the 20 side margins or vertical edges of the arcuately formed stereotype while the bottom edge of the stereotype is formed by a bottom clamp which secures the lower edge of the matrix to the drag member. The back 25 surface is defined by the cope member when lined with the heat insulating sheet material. The manner of supporting the respective mold members in co-operative relation will now be described.

30 The pedestal 11, as stated, comprises a support for the cope and drag members. The cope member may be held in rigid relation with the base member in any convenient manner, as, for instance, screw members 14 which may extend through the wall of the pedestal portion 11 and engage a bottom supporting flange 15 formed on the cope member 13. The drag member is arranged to be swung and shifted into co-operative relation with the cope member 13 to the position shown in Figs. 1 and 2, about pin members 17 secured to the lower end of the drag member and which engage upwardly extending plates 18 mounted upon the sides 35 of the bed member 10. The pins 17 are arranged to engage the plates 18 in suitably formed grooves 19 to permit the drag member 12 to be shifted along the surface of the pedestal and when clear of the pedestal portion to permit the drag member to drop slightly whereupon the drag member may be swung about the center of the pin members 17 to a horizontal position when they are resting in the depressed portion 19^a of 40 the grooves. Bracket members 20 may be provided which support a handle 21 of any suitable insulating material to permit the manual swinging of the drag member immediately after the molding operation. The 45 bed may have an opening 7 therein to clear the handle when the drag member is swung downwardly to its horizontal position.

Suitable means is provided for locking the respective mold members together. I 50 prefer to have the locking action serve to

more firmly secure the matrix and insulating sheeting to the drag and cope members respectively as will be presently set forth. The locking mechanism may comprise U-shaped handle levers 22 provided with 70 handle portions 23 at their outer ends and having top and bottom legs or lever portions pivotally mounted on lever members 24. The lever members are preferably of a U shape whereby they may be secured to the 75 back of the cope member adjacent the sides thereof and extend over the sides of the drag member to the rear thereof whereby inner ends 22^a of the lever members 22 may engage camming or locking blocks 25 secured to the rear face of the drag member. The hand levers 22 may be sung outwardly about pin members 24^a, which secure the levers to U-shaped levers 24, clear of the drag member to a position in the rear of 80 the cope member. This swinging movement taking place about the pin members 24^b. I find that such a lever arrangement is very effective in clamping or locking the respective mold members together.

To separate the mold members, I prefer to use simple parting means mounted upon the cope member and acting upon the sides of the drag member which may comprise circular cam members 30 eccentrically mounted upon a shaft 31 which is carried by suitable bracket members 32 secured to the back face of the cope member. A manually operated lever 33 of any convenient form may be rigidly mounted upon the shaft member 31 whereby an upward movement of the handle 33 will cause the cam members 30 to bear against the side edges of the drag member and bring about a parting of the respective mold members.

The means for suspending and uniformly supporting the matrix within the mold when formed arcuately upon the drag member may comprise clamping bars 40 mounted on small arms 41 pivotally mounted upon supporting blocks 42 secured to the sides of the drag member. The bars 40 may swing about the pivot rods 43. These clamping bars may comprise a body portion 40^a and clamping portion 40^b, which, when the block 40 is swung inwardly to a seated position against the surfaces 44 of the drag member, engage the side edges of the matrix. The bars 40 extend the complete height of the drag member 12 and the surfaces 40^c thereof which define the side edges or margins S' of the stereotype S. I prefer to also clamp the top edge of the matrix to the drag member and for this purpose, I may provide C clamps 50 which may engage an arcuate clamping band 16 which secures the top edge of the matrix to the drag member. A similar arcuately formed band 26 may be used to clamp the bottom edge of the matrix to the drag mem-

ber. This member serves also to close the bottom of the mold.

A convenient means for clamping the insulating lining to the cope member 13, may 5 comprise flat spring members 45, secured to the back surface of the cope member. These members may have a spring loop 45^a which extends beyond the side edges of the cope member and curves inwardly to provide an 10 engaging portion 45^b and a finger portion 45^c whereby the spring members may be grasped and deflected outwardly to permit the positioning of the side edges of the paper lining therebeneath.

15 The carrying out of the steps of my process when forming an arcuate stereotype such as has been herein referred to and which the present apparatus is adapted to mold, is as follows:-

20 The usual matrix M is placed upon the inner arcuate surface of the drag member 12, (the drag member 12 being in a horizontal position to permit convenient positioning of the matrix thereon), and the 25 clamping bars 40 are swung inwardly with the clamp portions 40^b engaging the side edges of the matrix. The matrix should be cut to the proper width whereby the side edges will be thus disposed beneath the 30 clamp portions 40^b of the bars, as illustrated in Fig. 3, the base serving to correctly position the matrix.

The bottom clamping band 26 and the top clamping band 16 are then positioned along 35 the bottom and top edges of the matrix. The insulating lining L (preferably comprising thin unglazed news print paper) may then be placed upon the concaved face of the cope member, the spring members 45 being deflected and then released to engage 40 the edges of the insulating sheet. The upper portion of this sheet may be slightly stretched to engage a portion of the coniform surface of the cope member which affords the pouring gate of the mold. When 45 the matrix and the insulating sheet are being positioned on the arcuate surfaces of the drag and cope members respectively, they should be pressed with sufficient force to expel the air from between the matrix and the 50 concave surface of the drag member, and from between the insulating sheet and the convex surface of the cope member. The mold members are now conditioned for assembling and the drag member may be 55 swung upwardly to a vertical position and shifted in a horizontal direction into juxtaposition with the cope members. The clamp members 50 may then be placed upon the top edge of the drag member in engagement 60 with the top edge of the matrix. The spring clips 45 will now rest upon the outer face of the clamping bars 40.

The mold members will thus be positioned 65 for locking and the locking lever mechanism

may be swung about the pins 24^b to bring the lever portion 22^a of the levers 22 into engagement with the locking blocks 25. A complete inward movement of the levers 22 will thus draw the cope and drag members accurately together with a uniform arcuate space between the molding surfaces of the matrix and the insulating lining of the cope member. This locking movement likewise causes the side edges of the cope member to 70 press the lining into engagement with the inner faces of the bars 40. The spring members 45 are thus deflected to a disengaging position, as illustrated in Fig. 5. This locking movement also causes the bars 75 40 to firmly engage the edges of the matrix and likewise to engage the insulating lining L of the cope member and cause a further stretching thereof if the same is not in perfect engagement with the concaved surface 80 of the cope member.

The mold is now ready for the pouring operation which may be done in the usual manner by pouring the molten type metal in the gate which is formed by the coniform 90 surface of the cope member, which has been hereinbefore described.

It will be noted that the pouring gate of the mold is lined and the metal, when being poured from the ladle back and forth along the coniform surface of the pouring gate, will be insulated from the cope member, while the upper extension of the matrix insulates the upper portion of the drag member therefrom. The molten metal will 100 thus retain the major portion of its heat units and the temperature thereof will be sustained through a sufficient period after being poured to flow into all of the forming cavities of the matrix surface.

After the short period during which the molten metal solidifies the cope and drag members may be unlocked by an outward swing of the lever members 22, and an upward movement of the lever 33 will part the drag member from the cope member. The drag member may then be shifted away from the cope and swung downwardly to a horizontal position and the stereotype removed from the mold. The gate side of the stereotype form may then be trimmed along 110 a line formed by the matrix.

It is to be understood that my method of insulating surfaces of a molding apparatus to make feasible the casting of a thin stereotype plate having a uniform cross section is applicable to the forming of flat stereotype plates, as well as arcuate plates, and in fact is adaptable to the formation of stereotype plates of any shape.

From the foregoing description, it will be seen that by the use of my method, it is possible to greatly decrease the weight of the stereotype plate without in any way complicating or increasing the production 120 125 130

thereof. A distinct advantage in obtaining a thin plate is to be found in the designing of printing presses in that the rotatable elements or reciprocating elements which 5 carry the stereotype may be of considerably less weight, inasmuch as they have to carry and move a stereotype plate of less weight. Furthermore, there is a saving of time and material. This method of insulating the 10 mold members, while extremely simple in character, nevertheless results in a very economical production of stereotype plates whereof the printing characters are of an accurate uniform height from the rear surface of the stereotype plate to the type surface.

I claim:

1. In an apparatus for casting stereotype plates, the combination of a supporting base 20 member, a cope member rigidly mounted thereon, and a drag member movably mounted on a base member and adapted to be swung from an upwardly facing exposed position where a matrix may be mounted on it into position in cooperation with the cope member.

2. In an apparatus for casting stereotype plates, the combination of a base member, a 30 vertical cope member rigidly mounted thereon, and a drag member pivotally and shiftably mounted on the base member and arranged to be swung from a horizontal matrix inserting position to a vertical co-operating position with said cope member.

3. In an apparatus for casting stereotype plates, the combination of a base member, a 35 cope member rigidly mounted thereon, a drag member shiftably mounted upon the base member whereby the drag member may 40 be elevated from a horizontal matrix inserting position on the base member to a vertical cooperating position with the cope member, and means for clamping the matrix to the drag member comprising plate margin 45 forming members mounted on the drag member and serving as a spacing means between the cope member and the drag member.

4. In an apparatus for molding stereotype 50 plates, the combination of a base member, a cope member having a cone surface, means carried by the cope member for securing a sheet of heat insulating material upon a convex surface thereof, a drag member shiftably mounted upon the base member and arranged to be swung from a horizontal to a 55 vertical cooperating position with the cope member, said drag member having a concave surface, means carried by the drag member for securing a matrix upon said concave surface and means for clamping the respective mold members together.

5. In an apparatus of the character 60 described, the combination of a base member, a cope member rigidly mounted upon a

molding surface thereof, a relatively movable drag member mounted upon the base member, means for securing a heat insulating lining upon the molding surface of the cope member, and means for securing a matrix to the drag member, said second named means being arranged to act upon said matrix and said lining when the respective mold members are brought into cooperative relation.

6. In an apparatus of the character described, the combination of a cope member having means for securing a heat insulating lining to the molding surface thereof, and a drag member having means for securing a heat insulating lining in the nature of a matrix upon the molding surface thereof, and means for clamping the respective mold members together.

7. In an apparatus of the character described, the combination with a cope and drag members, of heat insulating means lining the surface of the mold members, and clamping means securing the heat insulating means to the respective mold members.

8. In an apparatus of the character described, the combination of a cope member mounted upon a base and provided with means for securing a heat insulating lining to the molding surface thereof, and a drag member having means for securing a heat insulating lining to the molding surface thereof, said last named lining comprising a matrix and both of the mold members having heat insulated extensions comprising the 100 mold gate.

9. In an apparatus of the character described, the combination of a drag member, a cope member, and means for suspending a heat insulating lining within a molding cavity formed by bringing the respective mold members together.

10. In an apparatus of the character described, the combination of a drag member having a concave surface, a matrix carried thereby conforming to said surface, a cope member having a convex surface, heat insulating means in the nature of fibrous sheet material covering said convex surface, means for securing the material to the 110 cope member, means for spacing the respective mold members to provide a molding cavity when they are brought together and means for clamping the mold members together.

11. In an apparatus for casting stereotype plates, the combination of a base member, a cope member rigidly mounted upon a molding surface thereof, a relatively movable drag member mounted upon the base member, means for securing a heat insulating lining upon the molding surface of the cope member, and means for securing a matrix to the drag member, said second named means comprising pivotally mounted side 125

- members carried by the drag member and arranged to act upon said matrix while defining the side margins of the stereotype plate when the mold is poured.
- 5 12. In an apparatus of the character described, the combination of a cope member having means for securing a heat insulating lining to the molding surface thereof, and a drag member having means for securing 10 a heat insulating lining in the nature of a matrix upon the molding surface thereof, both of said means serving to maintain portions of the lining in place within a pouring gate between the cope and drag members, 15 and means for clamping the respective mold members together.
13. In an apparatus for casting stereotype plates, the combination of a base member, a 20 cope member rigidly mounted thereon, a drag member shiftably mounted upon the base member whereby the drag member may be elevated from a horizontal matrix inserting position to a vertical cooperating position with the cope member, and means for 25 clamping the matrix to the drag member comprising side members mounted on the drag member and affording molding surfaces defining the side edges of the cast plate.
- 30 14. In an apparatus for molding stereotype plates, the combination of a base member, a cope member having a convex surface, means carried by the cope member for securing a sheet of non-conductive material 35 upon the convex surface thereof, a drag member shiftably mounted upon the base

member and arranged to be swung from a horizontal to a vertical cooperating position with the cope member, said drag having a concave surface, means carried by the 40 drag member for securing the matrix upon said concave surface, said means serving to also space the cope and drag members apart a distance corresponding to a multigraph type height and affording molding surfaces 45 defining the side margins of the cast plate.

15. An apparatus for casting curved stereotype plates, consisting of a mold member having a concave face, a stereotype matrix on such face, a cooperating mold member having a convex face, and a paper liner 50 stretched on such convex face.

16. An apparatus for casting curved stereotype plates, consisting of a mold member having a concave face, means for holding a 55 stereotype matrix on such face, a cooperating mold member having a convex face, and means for holding a paper liner stretched about such convex face.

17. An apparatus for casting curved stereotype plates, consisting of a mold member having a concave face, means for holding a stereotype matrix on such face, a cooperating mold member having a convex face, 60 means for holding a paper liner stretched about such convex face, and means whereby the latter holding means is moved to idle position consequent upon the closing of the mold.

In testimony whereof, I hereunto affix my 70 signature.

HARRY C. GAMMETER.
